Inventor,

Milton Tibbetts.

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed September 27, 1919. Serial No. 326,922.

This invention relates to hydrocarbon motors, and particularly to means for heating the mixture passing from the carburetor to the motor.

5 One of the objects of the invention is to provide an extremely simple heater device that may be readily attached to a motor intake piper or header.

10 Another object of the invention is to provide a motor intake device of the combustion type having a circuitous outlet passage for the burnt gases to thereby more thoroughly heat the device and insure against passage of flame into the motor intake header.

15 Another object of the invention is to provide a heater device of the combustion type in which the igniter is arranged at a point where the incoming gases turn at substantially right angles in passing through the device.

20 Another object of the invention is to provide a heater device with simple and practicable means for speeding up the incoming gas and breaking up the particles of liquid fuel carried thereby.

25 Other objects of the invention will appear from the following description taken in connection with the drawings, which form a part of this specification, and in which:

30 Figure 1 is a side elevation of a motor intake pipe with a heater device built in accordance with the present invention connected thereto, the heater device being partly in section;

35 Figure 2 is a vertical sectional view on the line 2—2 of Figure 1; and

Figure 3 is a detail section on the line 3—3 of Figure 2.

40 Referring to the drawings, 10 represents a motor intake pipe or manifold having a throttle valve 10' therein. The intake pipe is shown as vertically arranged, though it will be understood that it may extend in any other desired direction, dependent largely upon the location of the carburetor of the motor relative to the intake passages in the cylinder block.

45 The heater device of this invention is in-

dicated in general by the numeral 11 and it 50 comprises a body part 12 forming a chamber 13 in which combustion is adapted to take place. The heater portion of the device is in the form of an extension 14, which may be integrally formed and which is preferably of cylindrical or tubular shape as shown particularly in Figures 2 and 3. At the junction of this tubular portion and the body portion 12 of the device, means are provided for securing the device to the motor 55 intake pipe above the throttle valve 10'. As shown, this means comprises exterior threads 15, and the intake pipe 10 is provided with a threaded opening 16 through which the portion 14 extends and by means of which 60 a tight joint is made and the device is secured to the intake pipe.

At right angles to the extension 14 is an inlet conduit 17 for the chamber 13. This conduit is formed by a boss 18 integral with 70 the body portion 12 of the device and by a hollow plug 19 which is threaded into the boss 18. Adjacent one end of this conduit 17, means are provided for breaking up the particles of fuel that are carried by or form 75 part of the mixture, and as shown this means is in the form of a screen 20 which is removably secured between the hollow plug 19 and the boss 18, thus making it an easy matter to change the size of the screen or 80 to remove the screen for cleaning.

At the other end of the conduit 17 is a plate 21 having a small opening 22 therein, this opening being considerably smaller than the interior of the pipe 23 which supplies 85 the conduit 17 with mixture drawn from any suitable carbureting or mixing device. The pipe 23 is secured to the plug 19 by a pipe fitting 24 which also secures the plate 21 removably in position as shown in Figure 90 1. Thus the plate also may be removed and another substituted therefor to thereby vary the size of the opening 22 as may be required for different sizes of motors.

The conduit 17 is preferably formed of substantially conical shape as shown in Figure 1 with the smallest part adjacent the plate 21 so that the gas issuing through the

opening 22 will spread until it reaches the screen 20, where it will be broken up and more thoroughly mixed before it reaches the combustion chamber 13. This separated arrangement of the perforated plate 21 and screen 20 and the widening out of the conduit 17 from the plate to the screen are important features in producing a good mixture for the combustion chamber and in preventing the propagation of flame backward through the opening 22. Because of the size of this opening 22 the gas is speeded up to a point where there can be no backfiring.

15 Within the combustion chamber 13, and preferably substantially at the point where the gas turns at right angles to enter the extension 14, an igniter 25 is arranged. This igniter is shown in the form of a 20 spark plug of usual construction, though the points may be separated more than usual because the charge is fired in the combustion space at or less than atmospheric pressure.

For the purpose of permitting observation 25 of the flame within the combustion chamber to thus determine the operation of the device, a glass window 26 may be provided opposite the extension 14, as shown in Figures 1 and 2. The glass is retained by means of 30 a threaded ferrule 27.

In order to retain the burnt gases in the heater device long enough to keep it at a high temperature, and for the purpose of preventing the passage of flame into the 35 motor intake header, a circuitous passage is provided for the gases from the interior of the extension 14 out to the motor intake pipe. In the form shown, the two telescoped tubes 28 and 29 are arranged within 40 the extension 14. The tube 28 is somewhat smaller than the interior of the extension 14 and is closed or blind ended at its inner end, as at 30. Near its outer end it is formed with a series of openings 31 to permit the passage of gas from the interior of 45 the extension 14 of the tube 28. The tube 29 has a through passage 32 which permits the gases to pass from the inner end of the tube 28 to the interior of the intake pipe 10. 50 The outer end of the passage 32 may be branched as shown at 33 so that there are several outlet openings into the intake pipe. The tube 28 is formed at its outer end with an expanded or flanged part 34 which rests 55 against a shoulder 35 near the outer end of the extension 14. The outer end of the tube 29 is enlarged as at 36 and threaded into the end of the extension 14 so that it bears against the flange 34 of the tube 28 and thereby retains both tubes in position.

From the above it will be seen that the heater device may be readily attached to the intake pipe 10 of the motor and easily removed therefrom for inspection or repair.

60 It is a self-contained unit and requires only

to be connected to a mixture device for supplying mixture to the tube 23 and to an ignition circuit of the motor to supply current to the spark plug 25.

When in position as shown in the drawings, suction will be created in the intake pipe 10 as the motor is turned over by an electric starting motor or otherwise. This will draw a certain amount of mixture past the motor throttle valve 10' and also create 75 suction on the pipe 23 and thereby draw a certain amount of mixture into the combustion chamber 13 through the conduit 17. When a spark is formed by the igniter 25 the mixture in the chamber 13 will be ignited 80 and the hot burned gases will pass through the extension 14 into the intake header 10. The heated extension 14 and the heated gases passing therefrom will warm up the mixture 85 passing through the intake pipe 10 and the said mixture will be more readily fired when it reaches the motor cylinders. The device will operate until the ignition is cut off or the motor is stopped.

Other forms may be devised without departing from the spirit or scope of the invention.

Having thus described my invention, what I claim and desire to secure by Letters Patent is:

1. A heater plug comprising a combustion chamber and an inlet conduit, a screen in said inlet conduit, and a disk in said conduit spaced from the screen and provided with a small inlet opening constituting the sole 100 mixture passage to the chamber.

2. A heater plug comprising a combustion chamber having an inlet conduit, a detachable plate having a small opening forming the inlet to said conduit, and means for removably retaining said plate in position.

3. A heater plug comprising a combustion chamber having an inlet conduit, a screen removably retained in said conduit, and a plate removably retained in said conduit in spaced relation to said screen, said plate having an inlet opening.

4. A heater plug comprising a combustion chamber having an inlet conduit, a screen removably retained in said conduit, and a perforated plate removably retained in said conduit in spaced relation to said screen, said conduit being of somewhat conical form between said plate and screen with the smallest part of the conduit adjacent the plate.

5. A heater plug comprising a combustion chamber having an inlet conduit, a screen removably retained in said conduit, and a perforated plate removably retained in said conduit in spaced relation to said screen, said conduit widening out from the plate to the screen.

6. A heater plug comprising a main combustion chamber and an extension formed with a circuitous outlet passage, and a trans-

parent window in the wall of said chamber opposite said extension.

7. A heater plug having an elongated heater portion, a blind ended tube secured adjacent the outer end of said portion and extending longitudinally thereinto, said tube having openings adjacent its outer end, and
- a second tube entering the first tube and secured to the heater portion, said second tube providing an outlet from the interior of the first tube.

In testimony whereof I affix my signature.

MILTON TIBBETTS.
